UNITED STATES PATENT OFFICE.

HOWARD L. FISCHER AND CHARLES A. WARD, OF ST. PAUL, MINNESOTA, ASSIGNEES
TO BROWN & BIGELOW, OF ST. PAUL, MINNESOTA, A CORPORATION OF MINNE-SOTA.

DESIGN FOR A CALENDAR.

Application filed September 21, 1927. Serial No. 23,499. Term of patent 14 years.

To all whom it may concern:

Be it known that we, HOWARD L. FISCHER and CHARLES A. WARD, citizens of the United States, residing at St. Paul, in the county of Ramsey and State of Minnesota, have invented a new, ornamental, and original Design for Calendars, of which the following is a specification, reference being had to the accompanying drawing, forming part thereof.

We claim:

The ornamental design for a calendar as shown.

HOWARD L. FISCHER.
CHARLES A. WARD.
